(57) **CLAIM**

The ornamental design for a gripping device, as shown and described.

DESCRIPTION

FIG. 1 is a perspective view of a gripping device showing our new design and coupled to a robotic arm via an end effector having an actuator and a vision system.

FIG. 2 is a perspective view of the gripping device showing our new design.

FIG. 3 is a plan view of the gripping device in an open state showing our new design.

FIG. 4 is a back view of the gripping device showing our new design.

FIG. 5 is a bottom view of the gripping device in an open state showing our new design.

FIG. 6 is a right side view of the gripping device showing our design.

FIG. 7 is a left side view of the gripping device showing our design.

FIG. 8 is a front view of the gripping device showing our new design in an embodiment.

FIG. 9 is a bottom view of the gripping device in a closed state showing our new design.

FIG. 10 is a plan view of the gripping device in a closed state showing our new design.

FIG. 11 is a plan view of the gripping device in a gripping state showing our design.

FIG. 12 is a bottom view of the gripping device in a gripping state showing our design.

FIG. 13 is a perspective view of the gripping device in a gripping state showing our design.

The broken lines in the drawings represent environmental structure and depict portions of the gripping device that form no part of the claimed design.

The gripping device has the ability to pick up objects in a tightly spaced manner with the ability to manipulate those objects while having access to the top of the objects. This eliminates the need to have module specific loading mechanisms decreasing machine cycle time and eliminating system complexity, increasing machine uptime. The gripping device is an accessory tool to a robotic arm. The gripping device couples to the robotic arm via a universal end-effector.
